UNITED STATES PATENT OFFICE.

ANTON RUDOLF MÖLLER, OF EVERETT, MASSACHUSETTS.

VALVE.

1,310,954.

Specification of Letters Patent.

Patented July 22, 1919.

Application filed March 15, 1919. Serial No. 282,864.

To all whom it may concern:

Be it known that I, ANTON RUDOLF MÖLLER, a subject of the King of Sweden, residing at Everett, county of Middlesex, State 5 of Massachusetts, have invented a certain new and useful Improvement in Valves, of which the following is a specification, reference being had therein to the accompanying drawings.

10 The invention relates to new and useful improvements in throttle valves of the particular type known as modulation valves. It is especially intended for use with radiators employed in hot water and steam heating systems although not limited to such use. It is perhaps more particularly advantageous in connection with hot water systems. In both of the above mentioned heating systems, but more especially in hot water 20 systems, it is frequently the case for one reason or another that there is more free circulation in some parts of the system than in others, thus causing an uneven distribution of the heat which should be met by proper 25 adjustment of the radiator valves.

One object of the present invention is to provide an adjustable throttle arranged in the valve body so that the size of the passage for the hot water or steam even when the 30 main valve is fully opened or lifted from its seat may be varied according to the adjustment of the throttle so as to obtain an even circulation and distribution of heat throughout the system. The valves in the several 35 radiators should be adjusted according to the requirement shown by experimentation when the system is installed so that there will be equal circulation in all of the radiators when all of the main valves are fully 40 open. If an adjustable throttle device is not employed it is impossible to maintain an even distribution or circulation except by variation in the sizes of the valves employed in the several radiators according to the differences in circulation, and even by the use 45 of variable sized valves it is practically impossible with the ordinary valve to secure an equal distribution of pressure in the different radiators because the valves are not graduated in sizes sufficiently close to meet the differences in pressure in the different radiators. My invention enables each valve 50 to be adjusted to all the variations in pressure within certain limits.

Another object of the invention is to provide an adjustable throttle which can be actuated by the stem of the valve. 55

The invention will be fully understood by reference to the following description when taken in connection with the accompanying 60 drawings and the novel features thereof will be pointed out and clearly defined in the claims at the close of this specification.

In the drawings, Figure 1 is a vertical section of a valve embodying my invention 65 showing the main valve and throttling mechanism closed.

Fig. 2 is a horizontal section on line 2—2 of Fig. 1.

Fig. 3 is a vertical section taken on the 70 same line as Fig. 1 but showing the valve wide open, the throttling mechanism being adjusted to such position that when the main valve is wide open the throttle valve will also be wide open. 75

Fig. 4 is a section on line 4—4 of Fig. 3.

Fig. 5 is a detail view of the throttle cylinder.

Fig. 6 is a detail view of the valve stem having the bit or wing projection thereon 80 for actuating the throttle cylinder.

Fig. 7 is a side elevation showing the adjustable bonnet and stop and the scale.

Fig. 8 is a sectional view of the bell and stop pin connected therewith. 85

Referring now to the drawings, 1 represents the valve body which is formed at one end with a nipple portion 2 tapped out for connection with an inlet pipe. It is also provided with a nipple portion 3 connected 90 with one side of the valve body adapted for connection with a radiator.

A bonnet 4 is screwed into the upper end of the valve body 1 and is formed with a central bore for the passage of the valve 95 stem 5, the lower portion of said bore being tapped out to engage the threaded portion of the stem 5.

The lower end of the stem 5 is connected with a valve disk 6 formed with a conical 100 lower portion 7 which is adapted to be seated upon the cone shaped annular seat 8 within the valve body. The stem is provided with any suitable means for turning it to open and close the valve. In the drawings, the 105 stem is shown as provided with a wheel 9 for the purpose of operating it.

Positioned within the valve body 1 is a

hollow cylinder 10 which is rotatable on its axis and which I term a throttle cylinder. Preferably it is seated in an annular groove 11 formed within the annular flange or 5 shoulder 12 at the bottom of the larger diameter of the valve body. The said cylinder is rotatable within said groove 11 as a guide way. In order to keep the cylinder from jumping out of its grooved way, it is preferably formed with an annular lip 13 at 10 its upper end and a screw ring 14 which engages with the internal threaded portion 15 of the body may be screwed down into engagement with the said annular lip 13 to 15 hold the cylinder just tightly enough so that it will not jump or rattle and yet leave it free to be rotated.

The cylinder 10 is formed with a circular opening 16 in one side, preferably of the same diameter as the opening 19 from the 20 valve body to the nipple 3. When the cylinder 10 is positioned on its axis so that the opening 16 therein registers exactly with the opening 19 to the nipple 3 then there will 25 be the largest possible area of opening for the hot water or steam through the valve into the radiator. The said cylinder, however, may be turned on its axis so as to bring any fractional part desired of the opening 16 into alignment with the outlet opening 19 30 from the valve body. Means are provided whereby the said cylinder will be rotated when the main valve is rotated and means are also provided whereby when the main 35 valve disk is being opened the cylinder 10 will be caused to rotate so as to bring into registration with the radiator inlet passage 19 either the full opening 16 or any predetermined fractional part of said opening 16 40 according to the adjustment and then be stopped from further opening movement. The means for accomplishing this are as follows: The cylinder 10 is formed with one or more vertical guide ways 17 in its inner 45 periphery. One of such guide ways is all that is really necessary but it is preferable to have a plurality of such guide ways in order to secure a greater fineness of adjustment. These guide ways are formed by a 50 plurality of fins 18 extending radially inward from the inner periphery of the cylinder. In the drawings three of such guide ways are shown.

The stem 5 is provided with a laterally 55 extending projection 34 something after the manner of a bit on a door key which engages with one of the said guide ways 17. The engagement of the said projection 34 with the guide way is effected by a vertical sliding movement when the parts are being assembled and at such time the projection 34 60 may be made to engage with either one of the guide ways that may be thought best and is then retained in such engagement 65 until the stem is removed by unscrewing the

parts. By removing the stem it may be readjusted to engage with any one of the other guide ways.

When the valve stem is turned to open or close the main valve 6 it will cause the cylinder 10 to rotate thus changing the position of the opening 16 relative to the opening 19 to the radiator. The projection 34 on the stem will move up or down in the guide way 17 as the valve and stem move up or down. 75

Means are provided to limit the rotary movement of the stem 5 during the opening movement of the valve, said limiting or stop means being adjustable so that the stop will become effective just at the right time when 80 the cylinder has been rotated a sufficient distance to bring into registration with the outlet opening 19 just that fractional part of the opening 16 which is required according to previous experimentation for proper distribution of the water or steam. The preferred means for accomplishing the above 85 result is shown in the drawings and is as follows: An annular bell 20 goes loosely over the threaded shank 21 of the threaded bonnet 4 and has an annular flange 22 which is seated upon a shoulder 23 at the lower end of the shank portion 21 of the bonnet 4. The bell 20 also has a downwardly extending lip 24 which fits loosely outside of an 90 annular flange 25 projecting from the upper end of the body portion of the bonnet 4. Said bell is rotatable on its axis with relation to said bonnet before the bell is clamped to 95 its seat. After the parts are assembled and 100 adjusted, the bell is clamped against movement as will be hereinafter described. A stop pin 26 projects outwardly from the said downwardly extending lip 24 of the bell. An arm 27 secured to the wheel 9 or to the 105 stem 5 extends downward in such position that during the rotation of the stem of the valve the said arm 27 is adapted to engage with said stop pin 26. In the drawings, said arm 27 is shown as being part of an L-shaped member having the horizontal head 28 which is apertured to go over the tapered upper end of the stem 5 and may be pushed down so as to form a tight fit so that it will 110 rotate with the stem. It is immaterial just how the connection is made, the important feature being that it should be secured in some manner so that the arm 27 will be actuated by the rotation of the stem of the valve. 115

When the parts are assembled and adjusted, the bell 20 should be held firmly against rotation. The bell should be adjusted to such position that when the main valve 6 is opened by rotating the stem 5 thereby also rotating the cylinder 10, the arm 27 will come into engagement with the stop 26 to stop its further rotation when the cylinder 10 has been rotated far enough to bring as much of the opening 16 in the cylinder into registration with the outlet open- 120 125 130 135

ing 19 to the radiator as has been predetermined to be the proper degree of opening for the particular valve. This degree of opening will be determined by experimentation by the steam fitter when he installs the radiator.

Means are provided for clamping the bell in its adjusted position. The means shown are as follows: The shank 21 of the bonnet 10 4 is threaded exteriorly and a lock nut 29 is screwed down onto the shank 21 of the bonnet until it securely clamps the annular flange 22 of the bell 20 against the shoulder 23. A stuffing box nut 30 is then screwed 15 down onto the shank 21.

When the parts are assembled in the manner already described, the bell 20 being adjusted so as to bring the stop 26 into the proper position as will have been determined 20 by previous experimentation, the said arm 27 will, when the valve is opened to full extent permitted by the adjustment, be in contact with the stop pin 26. To close the valve the stem 5 will be rotated by means of 25 the handle 9, in a clockwise direction as usual with valves until the main valve 6 becomes fully seated on its seat 8. When the valve is to be opened it will be rotated counter-clockwise in the usual manner until 30 the arm 27 again strikes the stop pin 26.

It is obvious that the full range of opening movement, even when the cylinder 10 is adjusted so that the full area of the opening 16 is in alinement with the inlet opening 19 35 to the radiator should be less than a complete rotation, otherwise during the lifting of the valve 6 the opening 16 of the cylinder would come into registration with the opening 19 and rotate past the opening 19 and 40 again come around into alinement with the opening 19 and so on for as many times as the stem had to be rotated in order to fully raise the valve 6. For this reason therefore the thread 31 of the valve stem and the co- 45 operating internal thread of the bonnet 4 should be quick acting so as to rapidly lift the valve stem and the valve 6. Preferably the valve stem and bonnet are double threaded to secure this quick action.

50 Preferably the valve body will be provided with a scale 33 marked on its outer periphery just below the annular flange 24 of the bell which will indicate by the position of the stop pin 26 on the bell with relation to the graduated marks of the scale 55 to what extent the opening 16 in the cylinder comes into registration with the opening 19 of the inlet to the radiator when the valve 6 is fully raised from its seat.

60 What I claim is:

1. In combination with a valve body having an inlet opening for connection with an inlet pipe and provided with another opening adapted for connection with a radiator or other object to which water or steam

is to be admitted through the chamber in the body of the valve, a valve which controls the passage from the inlet pipe to the valve body, a hollow rotatable cylinder within said valve body having an opening in the 70 periphery thereof which during the rotation of the cylinder is adapted to be brought into position of varying degrees of alinement with the opening to the radiator according to the extent of rotation of the said 75 cylinder, and stop mechanism which limits the degree of opening movement of the cylinder, said cylinder being formed with a guide way on its inner periphery and said valve having a stem provided with a projection which engages with the said guide way 80 in the cylinder whereby during the rotation of the valve stem the said cylinder will be rotated on its axis.

2. In combination with a valve body having a screw down valve said valve body having an inlet and an outlet opening, a hollow throttling cylinder located within the chamber of said valve body, said valve body having an annular groove in which said cylinder is seated and is free to turn, said cylinder having an opening in its periphery, and means whereby the rotation of the valve 90 also rotates the said cylinder to bring the said opening in the cylinder into registration with the outlet opening from the valve body.

3. In combination with a valve body having a screw down valve, said valve body having an inlet and an outlet opening, a hollow throttling cylinder located within the chamber of said valve body and rotatable on its axis, said cylinder having an opening in its periphery which during the rotation of the cylinder is adapted to be brought into more 100 or less registration with the outlet opening from the valve body according to the degree to which the said cylinder is rotated, said cylinder having a grooved way on its inner periphery in the lengthwise direction of the 110 cylinder, and a valve stem connected with said valve and having a projection thereon which engages with said groove whereby the rotation of the valve stem rotates the cylinder.

4. In combination with a valve body having a screw down valve, said valve body having an inlet and an outlet opening, a hollow throttling cylinder located within the chamber of said valve body and rotatable on its axis, said cylinder having an opening in its periphery which during the rotation of the cylinder is adapted to be brought into more or less registration with the outlet opening from the valve body according to the degree to which the said cylinder is rotated, a shoulder within the valve body on which one end of said cylinder is seated in such manner as to be rotatable thereon, and a screw ring screwed into the 120 125 130

valve body and adapted to be screwed down into loose engagement with the other end of said cylinder in such manner as to retain the cylinder against axial movement 5 but sufficiently loose to permit rotary movement of the cylinder.

5. In combination with a valve body having a screw down valve provided with a valve stem, said valve body having an inlet 10 and an outlet opening, a hollow throttling cylinder located within the chamber of said valve body and having an opening in its periphery, means whereby the rotation of the valve stem rotates said cylinder, a bonnet 15 screwed into one end of the valve body and having an aperture through which the valve stem passes, said bonnet being formed with a shank and with an annular shoulder between the shank and the body of the bonnet, 20 and a bell which goes loosely over said shank and is seated upon said shoulder, being rotatably adjustable thereon, means for clamping said bell in its adjusted position, a stop 25 projection on said bell, and an arm connected with the valve stem which during the rotation of the valve stem is adapted to engage said stop to limit the opening movement of the valve stem and thereby determine the degree of registration of the opening 30 in the cylinder with the outlet opening from the valve body.

6. In combination with a valve body hav-

ing a screw down valve provided with a valve stem, said valve body having an inlet and an outlet opening, a hollow throttling 35 cylinder located within the chamber of said valve body and having an opening in its periphery, means whereby the rotation of the valve stem rotates said cylinder, a bonnet 40 screwed into one end of the valve body and having an aperture through which the valve stem passes, said bonnet being formed with a shank and with an annular shoulder between the shank and the body of the bonnet, and a bell which goes loosely over said 45 shank and is seated upon said shoulder, being rotatably adjustable thereon, means for clamping said bell in its adjusted position, a stop projection on said bell, an arm connected with the valve stem which during the 50 rotation of the valve stem is adapted to engage said stop to limit the opening movement of the valve stem and thereby determine the degree of registration of the opening 55 in the cylinder with the outlet opening from the valve body, and a graduated scale on the outside of the valve body whereby the degree of possible opening through the said cylinder for any predetermined position of the said stop will be indicated by the 60 position of the said stop with relation to the scale.

In testimony whereof I affix my signature.
ANTON RUDOLF MÖLLER.
